UNITED STATES PATENT OFFICE.

AUGUST DERAGOWSKI, OF PARSONS, KANSAS.

BANK PROTECTOR.

Application filed May 5, 1928. Serial No. 275,463.

This invention relates to an improved device to be hereinafter referred to as a bank protector, the same having more particular reference to a structure which is installed in 5 and upon banks and similar establishments to frustrate bank robberies.

Briefly, the invention involves the utilization of a multiplicity of guns and means for supporting these in an appropriate position 10 for firing a volley of shots in predetermined directions with the intent to kill bandits and to frustrate hold ups and robberies.

The invention embodies outside signal guns, and inside pistols, together with appropriate supporting means, and manually manipulated operated means located within the bank cages within convenient operating distance of the occupants of said cages.

In the drawings:—

20 Figure 1 is a fragmentary sectional view of a portion of a bank showing the cage structure, the outside signal guns, inside protecting pistols, and manual operating means.

Figure 2 is a top plan view of a portion of 25 the inside structure.

Figure 3 is a view observing the structure from the inside of the cage.

Figure 4 is a fragmentary perspective view of the foot controlled element.

30 Referring now to the drawings by numerals it will be observed that the bank is generally designated by the reference character 5 in Figure 1, the roof is designated at 6, and the shade structure generally designated at 7. These parts are of ordinary construction and arrangement.

In accordance with my invention I provide protective pistols 8 for disposition behind and above the cages; at opposed sides a 40 multiplicity of these pistols, the same being of ordinary repeating shot type. They are supported in predetermined and aimed position between upper and lower rails 9 and 10 respectively. The rail 10 is rigidly supported 45 in horizontal position and the rail 9 is bolted thereto to permit it to be removed for replacement and reloading of the pistols. The pistols are located between the two rails in different angular positions. Carried by the 50 rails 10 are brackets 11 having bearings for a rock shaft 12. Fastened on the rock shafts are sets of rocker arms 13 and 14, respectively. An operating cable, cord or other element 55 15 is connected with the arm 14 and a short pull cord 16 is connected with the arm 13 and in

turn connected with the trigger of the adjacent pistol. The rod 15 extends down and is connected with the hingedly mounted, foot actuated platform 17 normally held in non-operative position by spring means 18.

60 The platform 17 obviously serves to simultaneously operate a plurality of pistols which have operating connection with the oscillatory rock shaft.

On the roof 6 we find one or more guns 19, 65 each gun being fastened in place by brackets 20 and 21. The gun is intended to fire up into the air to give a loud report and a consequent signal to the police. Each gun is equipped with a small pulley 22 over which 70 a pull cord 23 extends. The pull cord is connected with the trigger of the gun and extends down through the openings in the structure 5 where it is connected at its lower end to the hingedly mounted foot pedal 24. The foot 75 pedal is located beneath the platform but it is individually operable.

With this arrangement it is obvious that the occupant of the cage will place his foot on the pedal 24 to fire the gun 19 to give a 80 signal. The signal is usually employed when there are patrons in the bank. It would be dangerous to shoot the pistols 7 in the event an intruder or robber enters.

85 However, by placing the foot upon the platform 7 and forcing downwardly, the rock shaft 12 is oscillated, and through the medium of the crank arm 13 and pull cord 16, the pistols 8 are simultaneously fired in various directions. These pistols are properly 90 trained or aimed to both scare the intruders and in many instances to shoot him or them, as the case may be.

In an apparatus of this kind it is believed 95 to be efficient and capable of fulfilling the requirement of a structure of this class in a dependable manner. The simplicity of construction and arrangement is such however, as to make it unnecessary to go into greater detail regarding the construction or the merits. Therefore, a further detailed description 100 will be omitted.

Minor changes in size, shape and rearrangement of parts coming within the field of the invention claimed may be resorted to if desired.

105 Having thus described the invention, what I claim as new is:—

In a structure of the class described, a bank building embodying an employees cage, up- 110

per and lower spaced supporting members associated with the upper edge of the cage, a plurality of pistols supported between said members, bearing brackets carried by the 5 lower supporting member, a rock shaft mounted for oscillation on the bearings of said brackets, rocker arms secured to the rock shaft, said arms being arranged thereon in pairs and adjacent each of said pistols, a flexible operating connection between one of said

arms of each pair and the trigger of one of said pistols, a foot actuated platform pivotally mounted within the cage, a rod extending from the other rocker arm of said pair for connection to said platform, for actuating the rock shaft whereby the pistols may be fired and spring means for normally holding the platform in a non-operative position. 15

In testimony whereof I affix my signature.

AUGUST DERAGOWSKI.
